United States Patent Office.

JOSEPH F. ALEXANDER, OF NEW YORK, N. Y.

Letters Patent No. 97,146, dated November 23, 1869.

IMPROVEMENT IN PROPELLING-APPARATUS.

The Schedule referred to in these Letters Patent and making part of the same.

To all whom it may concern:

Be it known that I, JOSEPH F. ALEXANDER, of the city, county, and State of New York, have invented a new and improved Undulating Propeller; and I do hereby declare the following to be a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is a similar view thereof, showing the propeller in a different position from the previous figure.

Similar letters indicate corresponding parts.

This invention consists in the arrangement of a bucket or blade, working in a chamber which is open at both ends, and extends in the direction of the keel of the vessel to be propelled, said blade being suspended at its ends from two cranks, situated at an angle of ninety degrees to each other, in such a manner, that by revolving the crank-shaft, an undulating motion is imparted to said blade, whereby the water in the propeller-chamber is displaced, and expelled either at one or the other end of said chamber, according to the direction in which the crank-shaft is turned; and thereby the vessel is propelled either forward or backward, with comparatively little expenditure of power.

In the drawing—

The letter A designates a shaft, to which a revolving motion is imparted by a steam-engine or any other motor, and which has its bearings in suitable boxes, in the interior of the vessel to be propelled, said shaft being placed in line with or parallel to the keel of the vessel.

On this shaft are secured two cranks B C, at an angle of ninety degrees (or nearly so) to each other, and each of these cranks connects by a rod, b or c, with a cross-head, e or f.

These cross-heads move in suitable slides D, and they connect, by rods g h, with the ends i j of a bucket or blade, E, which is enclosed in the propeller-chamber F.

This chamber is situated below the water-line, either in line with or parallel to the keel of the vessel to be propelled, and it is open at both ends, as shown in the drawings.

The edges of the blade E extend close to the sides of the propelling-chamber, and if the shaft A is revolved, the water contained in said chamber is displaced and forced out at one of the ends of the chamber, according to the direction in which the vessel is to be propelled.

If the shaft is turned in the direction of the arrow marked on it in fig. 1, the blade E will move from the position shown in fig. 1 to that shown in fig. 2, and

the water contained in said chamber is forced out in the direction of the arrow marked in the chamber in fig. 1.

If the motion of the shaft continues until the end i of the blade E reaches the top of the propelling-chamber, the end j will be brought again to the centre of said chamber, and the water will continue to be displaced in the direction of the arrows marked in said chamber in fig. 1, and the vessel will be propelled in the direction opposite to said arrows.

If the motion of the shaft A is reversed, as indicated by the arrow marked thereon in fig. 2, the water in the chamber F will be displaced in the direction of the arrows marked in said chamber in fig. 2, and the motion of the vessel will be reversed.

The effect of the blade E to expel the water from the chamber F, either in one or the other direction, without interruption during its entire motion, is due to the position of the cranks B C at right angles to each other.

If these cranks were placed at angles of one hundred and eighty degrees to each other, the water, during one half of the stroke of said blade, would be expelled at one, and during the other half, at the opposite end of the chamber F; and if the cranks B C were placed in the same direction, the water would be expelled from the chamber F simultaneously at both ends; but by placing the cranks at an angle of ninety degrees, the blade receives an undulating motion of such a nature that the water will be continually expelled either at one or at the other end of the chamber F.

The joints at the ends of i and j of the blade are double, as shown, so that the blade E is free to accommodate itself to the positions of the rods g h.

It must be remarked that two or more propeller-blades can be applied either in the sides or at the stern of one and the same vessel, and said blade or blades might be worked freely in the water without any chamber, and it or they can be placed either in a vertical or horizontal position, and applied to any part of the vessel, either inside or outside, below the water-line.

It is obvious that the cranks might be replaced by eccentrics, without changing the result.

Having thus described my invention,

What I claim as new, and desire to secure by Letters Patent, is—

The blade E, situated below the water-line, and connected to two cranks B C, situated at a suitable angle toward each other, substantially as shown and described.

JOSEPH F. ALEXANDER.
